UNITED STATES PATENT OFFICE.

HARRY H. RALPH, OF PHILADELPHIA, PENNSYLVANIA.

PURIFIER FOR STEAM-BOILERS.

1,160,651.

Specification of Letters Patent. Patented Nov. 16, 1915.

Application filed February 16, 1915. Serial No. 8,589.

To all whom it may concern:

Be it known that I, HARRY H. RALPH, a citizen of the United States, residing at the city of Philadelphia, in the county of Philadelphia and State of Pennsylvania, have invented certain new and useful Improvements in Purifiers for Steam-Boilers, of which the following is a specification, the present invention being an improvement 5 upon the apparatus described and claimed in United States Letters Patent granted to me under date of December 8, 1914, and numbered 1,120,405.

The purifier for steam boilers set forth 15 in the above patent, while proving generally satisfactory in use, has demonstrated the practicability of making certain changes to render the same more efficient and commercially valuable.

20 Among other things, practice has demonstrated that during excess or forced feeding of water to a boiler, or in the case of a boiler working on an overload, an overflow or leakage of solids from said purifier takes place, 25 which solids in falling among the boiler tubes adhered thereto. Such overflow or leakage of solids is caused by undue agitation at the inlet end of the purifier and instead of all the solids precipitating to the 30 purifier bottom quantities thereof escaped to the boiler through the ports of the purifier.

To overcome the above-recited disadvantageous features, to provide for a maximum 35 amount of precipitation of solids; and to provide certain new and novel arrangements and combinations of parts for producing a more efficient and commercially valuable purifier for steam boilers, are the principal 40 objects of the present invention.

With these and other objects in view, the invention consists of the improvements hereinafter described and finally claimed.

The nature, characteristic features and 45 scope of the invention will be more fully understood from the following description, taken in connection with the accompanying drawing forming part hereof and in which:

Figure 1, is a view in section of a steam 50 boiler equipped with a purifier embodying the invention, Fig. 2, is a view partly in elevation and partly in section of the purifier, detached. Fig. 3, is a view in cross-section, taken upon the line 3—3 of Fig. 1, 55 but drawn to an enlarged scale; and Fig. 4,

is a detail view of a check valve hereinafter referred to.

In the drawings, there is illustrated an ordinary horizontal tubular boiler 1, contained within which is the feed-water purifier 2, of the invention. As shown, the purifier consists of six sections bolted together as at 3, to form a casing. The number of sections, however, is immaterial. Leading to the purifier 2, from a pump not shown, is a feed-water inlet connection 4. The opposite end of the purifier 2, has leading therefrom a pipe 5, having a valve 6. This pipe may be connected with the valved blow-off 60 7, of the boiler 1. Adjacent the upper part of section *a*, of the purifier and upon each side thereof are openings or ports 8, and 9. Leading from these ports are pipes 10, and 11, of which the pipe 11, is shown as extending rearwardly and parallel with the sides of the purifier and the pipe 10, is shown as extending forwardly in like manner. The pipes 10, and 11, terminate in funnel-like members 12, which are horizontally disposed as shown and each pipe is provided with an 65 inwardly opening check valve. That part of inlet connection 4, located within the boiler and which may be coiled is provided with a funnel-like member 13, provided with an inwardly opening check valve. These 70 parts are all shown and fully described in my aforesaid patent. In addition to the openings or ports 8, and 9, section *a*, of the purifier is provided with openings or ports upon each side thereof which are designated 75 14, and 15. Pipes 16, connect with these openings or ports and are extended downwardly through the boiler to within a short distance of the bottom thereof. Section *b*, (which is immediately adjacent section *a*) and the extreme outer section *c*, of the purifier are provided with openings or ports from which extend in similar manner pipes 80 17, and 18. These various pipes are extended to pass between the boiler tubes 19, as clearly shown in Fig. 3. Each of these pipes is provided with an outwardly opening 85 check valve 20, see Fig. 4, which check valves are preferably placed adjacent the purifier casing, so as to provide in effect valved ports for the purifier. The free ends of the pipes 16, 17 and 18, stop immediately above trough-like receptacles 21, and 22, which receptacles as shown are suspended by straps 90 23, from the lower row of boiler tubes. The 95 100 105 110

top rims of the receptacles are turned inwardly at an angle, as at 24, see Fig. 3. The purpose of these pipes and troughs will presently appear.

5 Within section *a*, of the purifier, adjacent to the feed water inlet and preferably immediately to the rear of ports 8—9 is a vertically disposed baffle plate 24, which extends from the top of said section to within a short distance of the bottom thereof and preferably integral with said section. Extended at right angles from the back of said baffle plate substantially midway of the height of the section *a*, is a horizontally disposed baffle plate 25, preferably formed integral with said baffle plate and said section. Secured within adjacent section *b*, and preferably integral therewith is a horizontally disposed baffle plate 26, arranged in the same plane 10 as the baffle plate 25, and which in effect is a continuation of the latter. The combined baffle plates form a somewhat T-shaped construction. Obviously, if desirable the purifier section next beyond section *b*, may have 15 therein a baffle plate forming a continuation of baffle plate 26. The advantages of such arrangement of baffles will be explained in connection with the operation of the purifier to be presently described. Each section 20 of the purifier has preferably formed integral therewith, upon each side thereof, lugs 27, tapered as shown. At least some of these tapered lugs have fitted thereto screw-threaded stems provided with swiveled eyes 25. Straps 29, are secured to these eyes 28, and in turn are connected to eyes 30, fixed to the boiler top. This construction forms 30 means for suspending the purifier within a boiler in a rapid, cheap and efficient manner 35 and by reason of the screw-threaded connection between the lugs and swiveled eyes, uniform adjustments may readily be made.

In practice, it is endeavored to keep the water line within the boiler 1, even with the 40 funnel tops 12, and 13, so that the water outlet openings or ports are consequently below the water line, and it may be here remarked that normally pressure within the purifier 2, is slightly in excess of pressure 45 within the boiler. In feeding raw water, which usually contains silica, oxid of iron and alumina, lime and magnesia, to the purifier 2, it first impinges against the baffle plate 24, and the sediment in the water, 50 caused by the partial precipitation of the above solids as they pass through the heated portion of the inlet pipe 4, is directed to the bottom of the purifier which sediment tends 55 to settle within the chamber 31, that extends along the base thereof. In this connection 60 the baffles 25, and 26, or any continuation thereof, serve to further direct said sediment toward the chamber 31, during the agitation of water which occurs at the inlet end of the 65 purifier. With the introduction of water

within the purifier, the tendency of the water is to flow toward the extreme outer end of the purifier. By reason of the pipes 18, the feed water will first find its way to the boiler through these pipes, in contradistinction to trapping or backing up within the purifier. It will then gradually find its way to the boiler through pipes 16, and 17. The pipes 18, also serve to permit of the escape of air which may enter the purifier 70 with the feed water. 75

The above described arrangement of pipes permits of a gentle flow of feed water within the purifier, and also serves to permit of a maximum amount of precipitation of 80 solids, due to increased heating surface before delivery of water to the boiler. With the overfeeding of water to the purifier undue agitation occurs more or less throughout the purifier thereby permitting solids to pass 85 out through pipes 16, 17, and 18. These solids are collected within the troughs 21, and 22, at the boiler bottom, see Fig. 3. Thus practically no solids reach the boiler interior. In this connection, it is to be noted 90 that the parts 24, of the troughs tend to keep the solids within the troughs, although water may readily find its way to the boiler. It is to be noted that the pipes 16, 17, and 18, may be extended if desired, to what is 95 termed "dead points" in a boiler, particularly in marine and locomotive boilers, in order to increase circulation therein.

It is thought that the operation of "blowing off" the boiler together with the action 100 of the scum collectors will be understood by reference to my aforesaid patent without description thereof herein. However, it is to be noted that during the blow off operation, the valves 20, close so that any solids 105 within the troughs 21, and 22, cannot be sucked back into the purifier.

What I claim is:

1. A water purifier embracing a hollow casing made up of a series of sections bolted 110 together of which one end section is provided with an inlet connection and of which the opposite end section is provided with a port having an outwardly opening valve, a vertical baffle plate within the inlet section spaced apart from but immediately adjacent said inlet and extended from the casing top to within a short distance of the bottom thereof and a second baffle plate 115 abutting against the first mentioned baffle plate and extended horizontally of said section substantially mid-way of the height of the casing.

2. A water purifier embracing a hollow casing made up of a series of sections bolted 120 together of which one section is provided with an inlet connection and of which the opposite end section is provided with a port having an outwardly opening valve, a vertical baffle plate within the inlet section 125

spaced apart from but immediately adjacent said inlet and extended from the casing top to within a short distance of the casing bottom, and a second baffle plate abutting 5 against the first mentioned baffle plate and extended horizontally of said section and through at least one adjacent section substantially midway of the height of the casing.

3. In combination a steam boiler, a feed 10 water purifier including its complemental inlet connection located within the boiler said purifier being provided upon each side and at least at each end thereof with ports having outwardly opening valves, means for 15 collecting solids from the feed water supply located adjacent the boiler bottom and means for conveying said feed water to the boiler operatively connected between said valved ports and said solids collecting 20 means.

4. In combination a steam boiler, a feed water purifier including its complemental inlet connection located within the boiler said purifier being made up of a series of 25 sections bolted together, at least the end sections being provided upon each purifier side with ports having outwardly opening valves, means for collecting solids from the feed water supply located adjacent the boiler 30 bottom and piped connections operatively disposed between said valved ports and said solids collecting means.

5. In combination a steam boiler, a feed water purifier located within the boiler said 35 purifier being made up of a series of sections bolted together of which one end section is provided with an inlet connection and of which at least the end sections are provided with ports having outwardly opening 40 valves, a vertical baffle plate within the first-mentioned section immediately adjacent the inlet, a horizontally disposed baffle plate extended rearwardly from the vertical baffle plate, a medium for collecting solids 45 from the feed water supply located adjacent the boiler bottom and means for conveying feed water to the boiler operatively connected between said valved ports and said solids collecting medium.

50 6. In combination a steam boiler, a feed water purifier therein which purifier is provided with a complemental water inlet con-

nexion and with ports having outwardly opening valves, open top mediums for collecting solids from the feed water supply 55 deposited adjacent the boiler bottom said open tops being partially closed by inwardly extending flanged portions, and means operatively disposed between said ports and said solids collecting mediums for conveying 60 feed water to the boiler.

7. In combination a steam boiler, a feed water purifier therein having a complemental inlet connection and with ports having outwardly opening valves, boiler scum 65 delivering means operatively connected with the purifier, open top mediums for collecting solids from the feed water supply disposed adjacent the boiler bottom said open tops being partially closed by inwardly 70 extending flanged portions and means operatively disposed between said ports and said solids collecting medium for conveying feed water to the boiler.

8. In combination a steam boiler, a feed 75 water purifier made up of a series of sections bolted together, oppositely disposed tapered lugs for said sections, screw-threaded stems having swiveled eyes adjustably fitted to at least some of said lugs and means 80 connecting said eyes with the boiler top for suspending the purifier.

9. A water purifier embracing a hollow casing made up of a series of separable sections bolted together, of which one section is provided with an inlet connection, a vertical baffle plate within the inlet section spaced apart from but immediately adjacent said inlet and extending from the casing top to within a short distance of the bottom 90 thereof, which vertical baffle has formed integral therewith and extended horizontally therefrom a short section of baffle plate, and of which at least the adjacent section to the inlet section is integrally provided with a horizontal baffle plate forming a continuation of the horizontal baffle plate in the inlet section. 95

In testimony whereof, I have hereunto signed my name.

HARRY H. RALPH.
